Primary Examiner — Antoine D Davis(74) *Attorney, Agent, or Firm* — Michael Best & Friedrich LLP(57) **CLAIM**

We claim the ornamental design for a motion detector, as shown.

DESCRIPTION

FIG. 1 is a right front perspective view of a motion detector showing our new design;

FIG. 2 is a left top perspective view thereof;

FIG. 3 is a left bottom perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

Features of the drawings that are not considered part of the design currently sought to be patented have been shown in broken lines.
